UNITED STATES PATENT OFFICE.

CHARLES E. FAYLE, OF MONTREAL, QUEBEC, CANADA, ASSIGNEE TO JOSEPH E. WARD,
OF MONTREAL, CANADA.

SIGN.

Application filed September 8, 1925. Serial No. 54,885.

My invention relates particularly to electric signs of the type in which the figures, letters or other characters are of open channel cross-section, the channel presented by each character conforming to the shape of the character and being illuminated by electric lamps distributed throughout the channel.

The principal objects of the invention 10 are:

(a) To provide a sign of this type in which each figure, letter, emblem or other device will appear in a plurality of contrasting colors with the lines of demarcation 15 between the colors accentuated both day and night;

(b) To provide a sign of the above-mentioned type in which it will be possible to see the colors in their relative arrangement from all angles;

(c) To provide a sign in which the light will be uniformly diffused throughout each figure, letter, emblem or other device appearing thereon.

25 Other minor objects will appear as the description progresses.

To this end my invention consists of the combination, construction and particular arrangement of the parts hereinafter described 30 and illustrated and pointed out in the claims.

For full comprehension, however, of my invention reference must be had to the accompanying drawings in which similar reference characters indicate the same parts and wherein:

Figure 1 is a front elevation of an electric sign constructed according to my invention;

40 Figure 2 is a side elevation thereof; Figure 3 is a horizontal sectional view taken on line 3—3 Figure 1; and

Figure 4 is a detail fragmentary sectional view illustrating one of the support 45 brackets.

The accompanying drawings illustrate one embodiment of my invention in a sign consisting of the letter "N" in two contrasted colors which is sufficient to disclose the various features of the invention. It is to be distinctly understood however that some or all of the novel features of the invention may be applied to one or more groups of letters, figures, emblems and devices in gen-

eral in any number of colors without departing from the scope of the invention.

The embodiment illustrated consists of a base 2 having the letter "N" in relief thereon. This letter is of channel or trough cross-section, throughout the bottom 3 of the channel being provided with the usual electric lamp sockets 4 and being constituted by the base. A bead 30 is formed integrally with the top edges of the outer sides 5 of the letter serving the same purpose as the bead 14, in that it demarcates the boundary of the letter, the metal being folded on itself several times to produce the required thickness.

The letter is shown in two contrasting 70 colors 6 and 7, the former being the darker and being bordered by the latter. This color arrangement will be presently described in greater detail.

In signs of this channel type considerable 75 difficulty has been experienced in the past in accentuating the lines of demarcation between the colors and at the same time imparting to all of the colors the same degree of visibility particularly when the sign 80 is illuminated. This difficulty is overcome in the present construction by inner divisional walls 8 bounding the inner color 6 and being disposed substantially parallel to the outer walls 5 of the letter. These 85 divisional walls are slightly inclined from their inner edges outwardly to provide ample clearance for the electric lamps and are perforated throughout their entire areas, being preferably constructed of fine wire 90 mesh and preferably of double thickness, and they are suspended by brackets 10 in position with their inner edges spaced from the bottom 3 as at 12 and reinforced by 95 a stiffening bead 13, and with their outer edges in transverse alignment with the outer edges of the sides 5 and terminating in a continuous bead 14. This last mentioned bead may be of any preferred cross-section 100 and is located at a point beyond the outer end of the lamp filaments so that the rays of light therefrom will strike the rear but not the front face 15 of the bead. A shadow is thus produced on the front face and the bead is caused to stand out prominently 105 when the sign is illuminated, clearly marking the division between the colors. To render the bead conspicuous during the day it

is painted black or some color which will contrast with the colors of the sign.

The brackets 10 which are constructed of fine wire so that they will not be visible except from very short distances are detachable to permit the insertion and removal of the divisional walls as an internal unit for the purpose of facilitating painting and other repairs or to fit in with other designs 10 these brackets may be given width for effect.

The coloring of the sign thus constructed is carried out as follows, the specific colors referred to being by way of example only; the area of the bottom 3 with the exception 15 of a narrow margin is colored red and both sides of the divisional walls are made the same color or if desired the outer side may be colored to conform to and supplement the color of the margin; the marginal area 3^a 20 of the bottom, the outer side of the divisional wall, and the inner face of the outer wall are white, and the bead 14 black; while the base 2 is yellow. From the foregoing it will be seen that the middle portion of bottom 3 and the divisional walls combine to 25 form a dark colored "N" and the marginal area 3^a of the bottom 3 and the inner side of the outer wall 5 combine to form a light colored "N" bordering the dark colored "N" 30 so that the sign when viewed from any angle does not lose its distinctive shape.

The purpose of the multiplicity of perforations 20 throughout the entire area of the divisional walls is to uniformly diffuse the light throughout the letter. The dotted arrows in Figure 3 clearly indicate the uniform diffusion which takes place, the light colored portions receiving substantially 35 the full intensity of the light.

40 If desired the outside walls may also be perforated to diffuse the light over the area of the base 2 surrounding the letter or the side walls may be cut out as indicated at 25 to indicate any desired device and the cut 45 out portion covered with a transparent or semi-transparent material colored or otherwise. The object is to make the whole or a portion of the wall pervious to light for the purpose of slightly illuminating the surface 50 of the base outside of the letter.

From the foregoing it is obvious that the divisional walls may be composed of a transparent or semi-transparent material, and that the number of contrasted colors and the 55 divisional walls forming the lines of demarcation may be varied as desired. I have

found from actual test that best results are obtained by coloring the letter immediately adjacent the lamps with a dark color as indicated by the red bottom in the embodiment 60 illustrated. When this portion of the letter is for instance, white, the reflection of the light is so great that it obscures the darker border portions.

Although the letter is shown in relief in 65 the illustrated embodiment it may be countersunk in the base if desired.

It is also to be understood that the divisional walls may be incorporated in signs previously constructed as a unit or as separate members and when applied to characters the channels of which are comparatively narrow the configuration of the walls may be scalloped or otherwise arranged to provide clearance for the electric lamps. 75

What I claim is as follows:

1. An electric sign of channel form having a divisional unit detachably mounted within the channel and substantially conforming to the shape of the latter, said unit 80 consisting of walls perforated throughout their entire area and supported in position with their inner edges spaced from the bottom of the channel and with their outer edges in transverse alignment with the outer 85 edges of the channel, and a continuous bead mounted upon the outer edges of the said perforated walls, and brackets detachably supporting the unit.

2. An electric sign appearing in contrasted colors consisting of a base, a character of channel cross-section carried by the base, said channel having a bottom and side walls and presenting an open front, a plurality of lamp sockets in the said bottom, 90 and combined means for accentuating the lines of demarcation between the colors and for diffusing the light throughout the channel, said means consisting of a unit comprising walls substantially conforming in shape 95 to the side walls of the channel and inclined from their inner edges outwardly, said walls being perforated throughout their entire areas, a bead on the outer edges of said walls, and means for suspending said unit in 100 position with the said bead accentuating the lines of demarcation between the contrasted colors. 105

In testimony whereof I have signed my name.

CHARLES E. FAYLE.
